(57) **CLAIM**

The ornamental design for a catheter clamp, as shown and described.

DESCRIPTION

FIG. 1 is a front perspective view of a catheter clamp in the closed position showing my new design;
FIG. 2 is a rear elevational view thereof;
FIG. 3 is a front elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a rear perspective view thereof;
FIG. 9 is a front perspective view of a catheter clamp in the open position showing my new design;
FIG. 10 is a front elevational view thereof;
FIG. 11 is a rear elevational view thereof;
FIG. 12 is left side elevational view thereof;
FIG. 13 is right side elevational view thereof;
FIG. 14 is a top plan view thereof;
FIG. 15 is a bottom plan view thereof; and,
FIG. 16 is a rear perspective view thereof.
